UNITED STATES PATENT OFFICE.

JAMES PRESTON, OF NEW YORK, N. Y., ASSIGNOR OF ONE-HALF TO SAMUEL A. BURNS AND C. A. COOK, OF SAME PLACE.

PUMP-FRAME.

SPECIFICATION forming part of Letters Patent No. 256,855, dated April 25, 1882.

Application filed June 30, 1881. (No model.)

To all whom it may concern:

Be it known that I, JAMES PRESTON, of the city, county, and State of New York, have invented a new and Improved Pump-Frame, of 5 which the following is a specification.

The object of my invention is to provide a new and improved pump-frame which facilitates changing the pump from a right-hand to a left-hand pump, and vice versa.

10 In the accompanying drawings, Figure 1 is a front elevation of a pump fastened to my improved pump-frame. Fig. 2 is a cross-sectional elevation of the same, and Fig. 3 is a horizontal sectional view of the same on line 15 *xx*, Fig. 1.

Similar letters of reference indicate corresponding parts.

The pump-frame consists of a plate, A, provided with two segmental or concave projections, B B, with grooves in the outer edges to receive two collars or annular projections, C C, of the pump-cylinder D, which is held to the plate or frame A by a semicircular or U-shaped band, E, fitting over a collar, C', of the 25 pump-cylinder. The pump-cylinder is thus free to turn on its longitudinal axis, so that the spout or nozzle F can be turned to project in any desired direction; but the cylinder cannot be moved vertically or laterally. A connecting-rod, G, is pivoted at its lower end to 30 the frame A, on the center line of the same,

and its upper end is pivoted to the pump-handle, near the upper end of the same. The upper end of this pump-handle H is pivoted to the piston-rod J, which is guided in a projection, K, at the upper end of the frame A.

If the pump is to be reversed—that is, if the handle is to be placed on the other side of the cylinder D—the upper end of the connecting-rod G is detached from the handle H, and the 40 latter is turned to the other side of the cylinder, when the rod G is again attached to it. The fulcrum of the handle H is at the upper end of the rod G, and swings to and from the piston-rod when the handle is worked.

I am aware that pump-cylinders have been secured to a supporting-frame so as to turn and bring the discharge-pipe on different sides; also, that fulcrum-supports for the handle have been pivoted to the frame; but

50 What I claim as new and of my invention is—

The handle fulcrum-rod G, pivoted at its lower end in the axial line of a turning pump-cylinder, and pivoted detachably to the pump-handle at the other end, whereby it will be in its true relative position to the handle, no matter to what extent the cylinder is turned.

55 JAMES PRESTON.
